UNITED STATES PATENT OFFICE.

MARY S. REATZ, OF KANSAS CITY, MISSOURI.

FRUIT-EVAPORATOR.

No. 845,317.

Specification of Letters Patent.

Patented Feb. 26, 1907.

Application filed June 30, 1905. Serial No. 267,770.

To all whom it may concern:

Be it known that I, MARY S. REATZ, a citizen of the United States, residing at Kansas City, in the county of Jackson and State of Missouri, have invented new and useful Improvements in Fruit-Evaporators, of which the following is a specification.

This invention relates to improvements in fruit-evaporators.

10 The object of the invention is to provide an apparatus by which fruit may be thoroughly and automatically dried.

The invention provides a chamber through which heated air is forced and having mounted therein an endless-belt conveyer, upon which the fruit is deposited at one end of the chamber and discharged from said chamber in a dried or evaporated condition.

20 The invention provides means for continuously driving the belt conveyer and means by which the fruit is evenly deposited upon the conveyer.

The invention provides, further, two endless-belt conveyers mounted in the drying-chamber, one discharging upon the other, the belt discharged upon conveying the evaporated fruit from the chamber, and means for driving said belt conveyers.

25 The invention provides, still further, means for reversible driving the belt conveyer discharged upon, the chamber having two discharge-openings disposed one at each end, the reversible belt conveyer being positioned so as to discharge through either opening, and 35 means by which fruit may be deposited upon one of both of said belt conveyers.

The invention provides, still further, means located at the discharge end of the belt conveyers for removing the fruit which fails to 40 drop by gravity therefrom.

The invention provides also a closure and discharge-chute adapted to be positioned interchangeably one at each of the discharge-openings of the chamber.

45 An additional feature of the invention consists in the opening in the roof of the chamber for the escape of vapor arising from the fruit and not carried from the chamber by the hot-air forcing means.

50 Other novel features are hereinafter fully described and claimed.

In the accompanying drawings, Figure 1 is a side view, partly in elevation and partly in vertical section, of the evaporating mechan-

ism. In this view the parts are represented 55 in the position suitable for driving the lower or receiving belt oppositely to the upper belt, the vertical section through the casing being taken on the dotted line *a b* of Fig. 2. Fig. 2 is a top view of the mechanism, showing 60 the chamber and some of the parts in horizontal section. Fig. 3 is a horizontal sectional view taken on the dotted line *c d* of Fig. 1, showing the worm-gear and some of the parts connected therewith. Fig. 4 is a transverse vertical section taken on the dotted line *e f* of Fig. 2. Fig. 5 is a vertical sectional view taken on the dotted line *a b* of Fig. 2, some of the parts being removed and part of the chamber being broken away. Fig. 6 is a 70 view similar to that of Fig. 5, the fan being omitted and the positions of closure 46 and chute 48 changed to ends of the casing opposite those at which they are located in Fig. 5.

Similar characters of reference denote 75 similar parts.

The drying-chamber may be a building of any suitable construction, preferably rectangular in form, and provided with two vertical end walls 1 and 2, having two discharge-openings 3 and 3', located, respectively, in the end walls 1 and 2, above the raised horizontal floor 4. The drying-chamber is provided with a roof 5, having in the comb, preferably along its full length, an opening 6 for the passage from the chamber of vapor arising from the fruit. A horizontal endless-belt conveyer, located in the drying-chamber and denoted by 7, has one end mounted upon a driving-roller 8, carried by 80 a rotatable shaft 9, mounted in suitable bearings in the upper ends, respectively, of two vertical posts 10, supported at their lower ends upon the floor 4, adjacent the wall 1 of the chamber. The other end of the belt 7 is 85 mounted upon a roller 11, carried by a horizontal shaft 12, rotatively mounted at its ends in the upper ends, respectively, of two vertical posts 13, the lower ends of which are supported upon the floor 4 adjacent the wall 100 2. Two parallel horizontal bars 14 are supported at their respective ends upon the posts 10 and 13 and have rotatively mounted between them a series of horizontal transverse rollers 15, which support the upper part of 105 the belt 7. Below the endless-belt conveyer 7 and parallel therewith is a similarly-constructed endless-belt conveyer 16, supported

at one end upon a horizontal roller 17, mounted upon and rotatable with a horizontal transverse shaft 18, which is rotatively mounted respectively in the upper ends of two vertical posts 19, supported at their lower ends upon the floor 4 adjacent the end 1 of the chamber. The endless-belt conveyer 16 is positioned so that it may discharge the fruit carried by it through either one of the openings 3 or 3', according to the direction the belt is driven. The other end of the belt 16 is mounted upon a roller 20, carried by and rotatable with a horizontal transverse shaft 21, the ends of which are rotatively mounted in the posts 13. Two horizontal bars disposed parallel with each other and denoted by 22 are supported, respectively, at their ends upon the posts 19 and 13 and have rotatively mounted between them and carried thereby a series of transverse rollers 23, which serve to support the upper part of the belt 16. The belt 16 has its end which is adjacent the end 1 of the chamber disposed, so as to have discharged thereupon the fruit carried by the belt 7. The belt 7 is always driven in the direction indicated by the arrow adjacent thereto in Fig. 1, said belt being driven by the roller 8 and shaft 9, the shaft 9 being driven by means of a pulley 24, secured at one end thereof and connected by means of a belt 25 with a pulley 26, (shown in Fig. 3,) which is rotatively mounted upon the shaft 18 outside the drying-chamber. The pulley 26 has thereon and integral therewith a worm-gear 27, which meshes with a horizontal worm 28, forming part of a horizontal shaft 29, rotatively mounted at one end in suitable bearings provided in a horizontal bracket 30, supported upon the upper end of a vertical post 31, which also supports the bracket 32, having in its upper end a bearing in which is mounted the other end of the shaft 29. The shaft 29 is driven by means of a bevel-gear 33 mounted thereon, which meshes with a bevel-gear 34, secured to the upper end of a vertical shaft 35, mounted in suitable bearings provided in the bracket 32, the lower end of the shaft 35 having secured to it a bevel-gear 36, which meshes with a bevel-gear 37, mounted on a horizontal driving-shaft 38, which in turn is rotatively mounted in vertical pillars 39, supported upon the ground. The shaft 38 is driven by a driving-pulley 40, secured on the shaft and driven by any suitable motor or engine. (Not shown.) On the shaft 12, outside the drying-chamber, is secured a pulley 41, which is connected by a belt 42 with a pulley 43, secured upon and rotatable with the shaft 18. When the belt 7 is driven in the manner hereinbefore described and the belt 42 is twisted as shown in Fig. 1, the belt 16 will be driven in the direction indicated by the arrows adjacent it in Figs. 1 and 5 through the intermediacy of

the roller 11, shaft 12, pulley 41, driving-belt 42, pulley 43, shaft 18, and roller 17. By reversing the belt 42 on the pulley 41, so as to make a straight driving-belt of it, the belt 16 is driven in the opposite direction, as indicated by the arrow adjacent it in Fig. 6, thus causing the belt 16 to discharge through the opening 3.

Over each opening 3 and 3' is a transverse strip 44 and 45, respectively, secured, respectively, to the end walls 1 and 2. A closure 46, comprising a vertical plate, is provided at its upper edge with a transverse lip 47, adapted to be interchangeably mounted upon either strip 44 or 45 for the purpose of closing the discharge-opening not in use. A chute 48 is provided with a lip 49, also adapted to be interchangeably mounted upon either strip 44 or 45, and when so mounted the shoe 48 is inserted in the adjacent opening in position to catch the fruit discharged from the belt 16. A brush 50 is mounted transversely in the chute 48 and is adapted when the chute is properly positioned in one of the discharge-openings to strike the lower side of the belt 16 and remove therefrom fruit which does not drop by gravity from the belt. Upon the outside of the end 2 of the drying-chamber are mounted two brackets 52, supporting between them two transverse rods 53, supporting thereon an incline hopper 54, one end of which extends through an opening provided therefor in the end wall 2 and which discharges fruit supplied therein to the upper side of the belt 7. A similar hopper 55, located below the hopper 54, has one end extending through an opening provided in the end 2 of the drying-chamber, so as to deposit fruit placed in the hopper upon the belt 16. The hopper 55 is mounted upon two transverse rods 56, having their ends supported, respectively, in the brackets 52. To provide an even distribution of the fruit upon the belts 7 and 16, the hoppers 54 and 55 have imparted to them a lateral movement to and fro relative to said belts. Movement of said hoppers in one direction laterally is caused by four compression-springs 57, mounted one upon each of the rods 53 and 56 and bearing at their ends, respectively, upon the adjacent hoppers 54 and 55 and one of the brackets 52. Movement of the hoppers 54 and 55 in the opposite direction laterally is caused by a reciprocatively-mounted rope 58, one end of which is secured to a crank-arm 59, the other end passing over a pulley 60, rotatively mounted on a bracket 61, secured to the chamber-wall 2, the latter-named end of the rope 58 having four branches 62, two of which connect to the hopper 54 and the other two connecting with the hopper 55 in such a manner that when the rope 58 is drawn in the proper direction by the crank-arm 59 the hoppers 54 and 55 will be forced on the supporting-rod laterally.

in a direction such that the springs 57 will be compressed. When the rope 58 is permitted to move in the opposite direction by the crank-arm 59, the compression-springs 57 will force the hoppers in the other direction.

Hot air is supplied to the drying-chamber by a hot-air pipe 63, one end of which is connected to a suitable furnace 64 and the other end of which discharges in the chamber adjacent the opening 3'. In the wall 1 of the chamber, adjacent the ends of the belts 7 and 16, are provided openings 65, through which the hot air from the chamber is forced outwardly by means of a fan 66, mounted on a longitudinal shaft 67, supported by suitable bearings and having secured thereto at its outer end a bevel gear-wheel 68, which meshes with a bevel gear-wheel 69, mounted on a horizontal shaft 70, rotatively mounted in a bracket 71. On the shaft 70 is secured a pulley 72, which is connected by a belt 73 with a pulley 74, secured upon the shaft 38. When the shaft 38 is rotated, the fan 66 is driven by the mechanism just described and forces the heated air from the pipe 63 to pass adjacent the belts 7 and 16 and thence from the chamber through the opening 65.

In operating my invention when the fruit is in condition requiring a comparatively long exposure to the heated air for evaporating the moisture carried by the fruit the belt 42 is twisted, as shown in Figs. 1 and 2, thus driving the belt 16 in the direction denoted by the arrow adjacent thereto in Fig. 1. The fruit, preferably sliced, is now fed into the hopper 54 and the driving-shaft 38 rotated in the proper direction by a suitable motor or engine. (Not shown.) The fruit from the hopper 54 will be evenly distributed on the belt 7, owing to the lateral movement imparted to the hopper 54 by means of the springs 57 and rope 58, as before described. The belt conveyers 7 and 16 will have a very slow movement imparted to them, thus slowly carrying the fruit in the current of heated air produced by the furnace 64 and driven by the fan 66 from the chamber by way of the openings 65, the air being supplied to the hot-air pipe 63 of the furnace from the exterior of the chamber in the ordinary manner common with hot-air furnaces. The fruit after reaching the end of the belt 7 adjacent the wall 1 is deposited by gravity upon the belt 16, by which it is carried in the reverse direction to the end of the belt 16 adjacent the wall 2, where it is deposited by gravity in the chute 48 and by it carried out of the building or chamber. Fruit sticking to the belts 7 and 16 will be scraped therefrom by the brushes 51 and 50, respectively. When the fruit is fed through the chamber in reverse directions, as described above, the closure 46 is applied to the opening 3, the chute 48 being placed in the opening 3', and no fruit is fed into the hopper 55. Moisture

in the chamber arising from the fruit and not carried by the fan 66 through the openings 65 will be carried through the roof-opening 6.

In some cases the fruit does not require to be exposed to the heated air but for a comparatively short time. In such cases I have

provided means by which the fruit may be carried through the chamber more rapidly and the capacity of the apparatus for evaporating much increased. In such cases the shaft 38, belt 7, and intermediate connecting parts and the fan 66 are driven as hereinbefore described. The furnace 64 is operated and the belt 42 untwisted or mounted on the pulleys 41 and 43 so as to drive said pulleys in a like direction, thus through the intermediary of the belt 7, drum or roller 11, shaft 12, pulleys 41 and 43, shaft 18, belt 42, roller 17 driving the belt 16 in the same direction as the belt 7, so that the belt 16 will discharge the fruit through the opening 3, in which the chute 48 is now inserted, the closure 46 being placed so as to cover the opening 3'. The fruit is now deposited in both hoppers 54 and 55, which are laterally vibrated by the springs 57 and the rope 58 operated by the crank-arm 59 on the shaft 38 and having the branches 62, which serve to draw the hoppers laterally so as to compress the springs 57, said springs when permitted so to do by the position of the rope 58 causing the hoppers 54 and 55 to be retracted laterally, thus evenly distributing the fruit upon the belts 7 and 16. The fruit carried by the belt 7 is discharged, as before stated, upon the belt 16, which belt carries the fruit so discharged and the fruit deposited upon it by the hopper 55 to the chute 48, by which it is carried from the chamber through the opening 3.

My invention may be modified in different ways without departing from its spirit.

Having thus described my invention, what I claim, and desire to secure by Letters Patent, is—

1. In a fruit-evaporator, the combination with a drying-chamber, of means for driving heated air therethrough, two endless-belt conveyers mounted in said chamber so that one discharges upon the other, a laterally-vibratory distributing means for depositing fruit upon said belts at like ends thereof, means for driving the upper belt, and means for driving the lower belt in either of two directions.

2. In a fruit-evaporator, the combination with a drying-chamber having a ventilating-opening in its roof, of means for forcing heated air horizontally through said chamber, two endless-belt conveyers disposed in the path of said heated air and discharging one upon the other, means by which fruit may be deposited upon one or both of said belt conveyers, means for driving the belt which discharges upon the other, and reversible means for driving the said other belt.

3. In a fruit-evaporator, the combination with a drying-chamber having discharge-openings at opposite ends, of an endless-belt conveyer mounted in said chamber so as to discharge at either of said discharge-openings, a closure and a chute having a brush for removing fruit from said belt conveyer, the closure and chute having means for being interchangeably positioned at said discharge-openings, and means for driving said belt in either direction.
4. In a fruit-evaporator, the combination with a drying-chamber having discharge-openings at opposite ends, of two endless belts disposed in said chamber so as to discharge one upon the other, the belt discharged upon being positioned so as to discharge at either discharge-opening, means for driving the belt which discharges upon the other, and reversible means for driving the belt discharged upon.
5. In a fruit-evaporator, the combination with the drying-chamber having discharge-openings at either end, of means for forcing heated air through said chamber, an endless-belt conveyer mounted in said chamber so as to discharge through either of said openings, an endless-belt conveyer for receiving thereon the fruit and positioned in said drying-chamber so as to discharge upon the first-named endless-belt conveyer, means for driving said second-named conveyer and means for driving in either direction the first-named conveyer.
6. In a fruit-evaporator, the combination with a drying-chamber having discharge-openings at either end, of means for forcing heated air through said chamber, two belts mounted in said chamber one discharging upon the other the belt discharged upon being positioned so as to discharge through either of said openings, means for depositing fruit upon one or both of said belts, means for driving in either direction the belt discharging at said openings, and means for driving the other belt.
7. In a fruit-evaporator, the combination with a drying-chamber having two discharge-openings one at each end, of means for forcing heated air through said chamber, an upper and lower endless belt mounted in said chamber the upper belt discharging upon the lower belt, laterally-vibratory means for depositing fruit upon said belts and means for driving the lower belt in either direction said lower belt being positioned so as to discharge at either of said openings.
8. In a fruit-evaporator, the combination with the drying-chamber having two openings one at each end, of means for forcing heated air through said chamber, an interchangeable closure for closing either of said openings, two endless belts mounted in said chamber one discharging upon the other, said other belt being positioned so as to discharge through either of said openings, means for driving the belt discharged upon in either direction, means for driving the belt discharging upon the other belt, and two laterally-vibratory hoppers for discharging fruit upon said belts respectively.

In testimony whereof I affix my signature in presence of two subscribing witnesses.

MARY S. REATZ.
